ATTORNEY

UNITED STATES PATENT OFFICE

HAROLD L. WARWICK, OF FORT WORTH, TEXAS, ASSIGNOR OF ONE-HALF TO GEO. B. McCARNEY, OF HANDLEY, TEXAS

SOUND RECORDING AND REPRODUCING APPARATUS

Application filed August 11, 1930. Serial No. 474,632.

My invention relates to a process of recording and reproducing in multiple, audible sounds; and the object is to provide a simple portable device for recording and reproducing news letters, speeches, lectures, court proceedings, musical programs, convention proceedings and the like in a simple portable apparatus, and to make the reproductions in indefinite number, and to make such recording and reproduction much more economical. The expensive disc records and films are dispensed with and the expensive needles are eliminated. Other objects and advantages will be fully explained in the following description and the invention will be more particularly pointed out in the claims.

Reference is had to the accompanying drawings which form a part of this application.

Fig. 1 is a diagrammatic view of the recording and reproducing apparatus, showing means for making a plurality of records, and means for demagnetizing or erasing the original record.

Fig. 2 is a diagrammatic view of a recording and reproducing apparatus.

Fig. 3 is a perspective view of a cabinet with the improvements applied therein.

Similar characters of reference are used to indicate the same parts throughout the several views.

The apparatus is provided with a supporting base 1 and bearing members 2 and spools 3 and 4 are journaled in these bearing members. Upright guide members 5 and 6 are provided and these guide members are provided with slots 7 for the passage of the recording wire 8. At the commencement of a recording operation, a spool 3 is provided with a wire 8. The spools 3 are carried in stock and ready for operation. The wire 8 is drawn off of spool 3 by any form of motor power and rolled on the spool 4. The spool 4 is provided with a shaft and a gear wheel 9 is rigid therewith and meshes with a pinion 10 which is provided with a shaft 11 to be driven by any suitable power. When the wire is passing from the spool 3 it is drawn through slot 7 in upright member 5 and tension means are provided for engaging the

wire 8 for controlling the speed of the passage of the wire 8 through the member 5. The wire 8 in leaving spool 3 to be wound on spool 4 passes a series of electromagnets. The first magnet 12 is provided for recording the sounds which come from the transmitter 13. The sound passes through wire 14 and battery 15, thence through a wire 16 through a transformer 17, and a wire 18 to the magnet 12. The circuit is completed by wire 19 which passes through the transformer 17 and back to the transmitter 13. The wire 19 is provided with a switch 20 for opening or closing the transmitter. A switch 21 is provided for opening and closing the sounding or reproducing device. This device consists of an amplifier 22 and a load speaker 23 connected in series with the transformer 17. By opening switch 21 and closing switch 20, the sounds will be recorded by magnetism on the wire 8 as the wire passes through the magnet 12. By reversing, that is, closing switch 21 and opening switch 20, the sound will be carried through the transformer 17 and amplifier 22 to the loud speaker 23 for reproduction. A series of magnets 24 are provided and the wire 8 runs through the magnetic field of the magnets 24. Wires 25 are electrically connected with magnets 24. Only one illustration of making permanent records is shown in Fig. 1. The wires 25 are electrically connected to the magnet 26. A wire 27 is run through the magnetic field of the magnet 26 to make a permanent record. It will be understood that wires may connect the other magnets 24 with duplicate magnets 26 for making permanent records on other wires 27. The mechanism for operating the wires 27 would be duplicates of the mechanism for operating the wire 8.

Means are provided for demagnetizing the wires 8 and 27 when desirable. A magnet 28 is provided with wires 29 which run to a battery 30 and a wire 8 is partly demagnetized and left in a uniform condition.

The wires which are to be formed into spools are thus magnetized and the wires are coated with chromium, copper or similar metal for protection and there may be any suitable number of yards of wire on the

spools. A single spool can be prepared with the records formed therein by the magnetism as above described, to afford an evening entertainment and it will not be necessary to change the records every four or five minutes. A spool 4 can be prepared with messages or musical impressions which will run 400 minutes or more if required. The metallic coating of the wire will maintain the 10 wire and the magnetic properties therein in condition to be reproduced. The coating protects the windings of the wire against adjacent windings of itself. After the metallic coating has been placed on the wire an 15 enamel coating is placed on the metallic coating.

I have produced a simple and portable apparatus that requires no expensive or complicated or bulky machine and which may be 20 used in any ordinary lecture room or hall to make a permanent record of music, lecture or speech, and afterwards reproduce this lecture or music amplified by any ordinary radio set and reproduced as many times as desired and that copies may be made simply on 25 cheap spools of ordinary steel wire and sold in any book or department store for a nominal sum. The length of wire in any one spool is of sufficient length to contain as many 30 hours of speech or music necessary at one recording.

What I claim, is,—

1. A sound producing apparatus comprising 35 a spool of magnetized wire, a metallic coating inclosing said wire, an enamel coating inclosing said metallic coating, said wire containing variable sound producing properties, and means for converting said properties into sound.

40 2. A sound producing apparatus comprising a spool of wire, a metallic coating inclosing said wire, means for magnetizing said wire and means for simultaneously creating sound producing properties in said wire including a sound transmitter.

45 3. A sound producing apparatus comprising a spool of wire, a metallic coating for said wire, an enamel coating for said metallic coating, means for magnetizing said wire and means for simultaneously varying the magnetic flux in said wire including a sound transmitter.

50 4. A sound recording and reproducing apparatus comprising a spool of wire, means for magnetizing said wire and means for simultaneously creating variable sound producing properties in said wire, a metallic coating for said wire, and electrical means for converting said properties into sound.

55 5. In testimony whereof, I set my hand, this 6th day of August, 1930.

HAROLD L. WARWICK.
